UNITED STATES PATENT OFFICE

JOHN E. ALLEN, OF MINNEAPOLIS, MINNESOTA

CIGARETTE CASE

Application filed August 1, 1929. Serial No. 382,731.

My invention provides an extremely simple and highly efficient cigarette case adapted to be used as a container of an original package of cigarettes and to operate under each opening movement to eject a cigarette from the container.

Generally stated, the invention consists of the novel devices and combinations of devices hereinafter described and defined in the 10 claims.

In the accompanying drawings like characters indicate like parts throughout the several views.

Referring to the drawings:

15 Fig. 1 is a perspective view showing the case as it appears when closed or in original condition;

Fig. 2 shows the case opened up but without cigarettes therein;

20 Figs. 3 to 7 inclusive are fragmentary views in the plane of lines marked 3—7 showing cigarettes without the case and illustrating different conditions or positions of the case section in respect to the closed positions; 25 and

Fig. 8 is a perspective view of one of the retaining bars removed from working position.

This improved case is adapted to be made 30 from a single piece of cheap material such as cardboard or quite stiff paper that is bent and folded to form two flat rectangular box sections 9 each of such depth as to hold one layer of cigarettes Y. The backs or outer 35 plates of the box sections 9 are formed with side flanges and with adjacent connected flanges, which latter are partially severed by rectangular cuts that form alternately projecting ejecting lips 10. The lips 10 project 40 alternately from the end flanges of the two box sections and the uncut portions 11, between the said projecting lips, afford a hinged connection between the two box sections.

The inner plates of the box sections are, 45 at one side, formed as extensions of the adjacent side flanges of said box sections and at their free side edges are preferably provided with flaps 12 that are tucked against and secured to the adjacent side flanges of the box 50 preferably attached thereto by glue or ce-

ment. At their extreme outer ends the box sections are provided with flaps 13 that are adapted to be tucked in the box section to close the outer ends thereof, as shown at the left in Fig. 2. The inner plates of the box sections, adjacent to their hinged edges, are formed with cigarette ejecting passages 14 that extend from side to side thereof and, as shown, are provided with central extensions or notches 15 so that the cigarettes can be 55 touched with the fingers and moved downward if at any time the cigarette sticks in the box. Normally the discharge of the cigarettes of the box sections is prevented by retaining bars 16, preferably of cardboard 60 strips with laterally bent ends 17.

This container made from paper or cardboard may be constructed at such small cost that it may be advantageously used as a container for cigarettes and may be loaded with 70 cigarettes and sold as an original package. In an original package both the retaining bars 16 will be in position, as shown in Fig. 3. To construct the device for delivery of cigarettes by opening movements, one of the bridge bars 75 will be moved, as shown in Fig. 4 so as to permit the cigarettes in the box section to drop down, as shown in Fig. 5. When the container is opened up, as shown in Figs. 6 and 80 7, the bottom cigarette of the box section from which the container has been removed, will be ejected by the interlapping alternate- 85 ly projecting lips 10 and moved outward, as shown in Fig. 6, and then as shown in Fig. 7, the cigarettes may be readily picked up with the fingers.

When the case is closed the cigarettes will naturally roll away from the returning lips 10 but if they do not they will be forced back by said lips so that the lips will engage and hold the next cigarette when the case is again opened. The lips 10 are quite flexible, and in some instances, to give the same increased flexibility, they have been made of tough 90 spring-acting paper and independently cemented. When the box is to be cheaply constructed the original container and the use of but one of the ejecting lips 10 will be found satisfactory even when stamped integral with 95 the box sections. The complete container 100

can be made from a single sheet of paper. This is desirable where extreme cheapness of construction is required but in some instances the container may be made of several paper sheets connected by cement or otherwise. It may, however, be made from sheet metal but this has been desirable only where the container is to be refilled and used over and over again.

If one of the box sections has been emptied of the cigarettes it will, of course, be necessary to remove the retaining bars 16 from the other box section so that the cigarettes contained in the latter will be successfully ejected under box opening movement.

What I claim is:

1. A cigarette case comprising two box sections hingedly connected, provided at their hinged edges with alternately projecting ejecting lips, the inner walls of said box sections having cigarette ejecting passages for delivering the cigarettes one at a time to the ejecting lips under case opening movements, removable cigarette retaining devices applied to the box sections for the normal delivery of cigarettes to said ejecting lips.

2. The structure defined in claim 1 in which said retaining devices are in the form of flat bars with laterally bent ends and engaged with the sides of the respective box sections and readily removable therefrom through said cigarette ejecting passages.

In testimony whereof I affix my signature.

JOHN E. ALLEN.
